UNITED STATES PATENT OFFICE.

ROBERT H. HEMPHILL, OF HATTIESBURG, MISSISSIPPI.

DESIGN FOR A SODA-WATER FOUNTAIN.

SPECIFICATION forming part of Design No. 33,347, dated October 9, 1900.

Application filed May 15, 1900. Serial No. 16,828. Term of patent 14 years.

To all whom it may concern:

Be it known that I, ROBERT H. HEMPHILL, a citizen of the United States, residing at Hattiesburg, in the county of Perry and State 5 of Mississippi, have invented and produced a new and original Design for a Soda-Water Fountain, of which the following is a specification.

The invention relates to a new and original design for a soda-water fountain; and it has for its object to provide a design of this character which will be both ornamental and useful.

The leading feature of the design consists 15 in the design forming the subject-matter of the accompanying illustration.

The figure of the drawing is an elevation of a soda-water fountain, showing my new and original design.

Referring to the drawing, 1 designates a vertical cylindrical tank provided at its lower end with the annular inclined flange 2, forming a trunco-conical base, and projecting out-

ward beyond the plane of the vertical sides of the tank. The top of the tank is arched 25 or dome-shaped, and it presents a convex upper face. The tank is provided at one side, between the dome-shaped top and the inclined annular flange 2, with the approximately inverted-J-shaped tube 4, consisting 30 of a vertical body-portion and the curved top portion 6, of approximately semicircular form, extending outward and downward from the vertical body portion, which is spaced from the tank.

What I claim is—

The design for a soda-water fountain herein shown and described.

In testimony that I claim the foregoing as my own I have hereto affixed my signature in 40 the presence of two witnesses.

ROBERT H. HEMPHILL.
